Primary Examiner — Angela J Lee*Assistant Examiner* — Liv C Anderson(74) *Attorney, Agent, or Firm* — Xia Li**CLAIM**

The ornamental design for a 3D light strip, as shown and described.

DESCRIPTION

FIG. 1 is a perspective view of a 3D light strip showing our new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof, the bottom plan view being a mirror image thereof;
 FIG. 7 is a perspective view of the 3D light strip where the 3D light strip is in a configuration of use; and,
 FIG. 8 is an enlarged view of portion 8 shown in FIG. 1. The dash-dash broken lines in the FIG. 7 depict environment of the 3D light strip that form no part of the claimed design. The dot-dash broken lines represent the boundary of the enlarged portion and form no part of the claimed design.
